UNITED STATES PATENT OFFICE.

HERMAN GOETTSCH, OF CHICAGO, ILLINOIS, ASSIGNOR OF ONE-HALF TO
THE J. W. SEFTON MANUFACTURING COMPANY, OF SAME PLACE AND
ANDERSON, INDIANA.

DESIGN FOR A PAPER BOX.

SPECIFICATION forming part of Design No. 24,277, dated May 7, 1895.

Application filed December 17, 1894. Serial No. 532,107. Term of patent 7 years.

To all whom it may concern:

Be it known that I, HERMAN GOETTSCH, a citizen of the United States, residing in the city of Chicago, county of Cook, and State of Illinois, have invented and produced a certain new Design for Paper Boxes, of which the following is a description, reference being had to the accompanying drawing, forming part of this specification.

10 The design relates particularly to paper boxes adapted to hold small quantities of confections, pop-corn, &c.

Referring to the drawing it will be seen that the box is rectangular in shape and bears 15 a general resemblance to a railway car. The top or roof is sloping and at its ends projects slightly over the ends of the car. The sides

of the box bear the representation of a series of windows, and the semi-circular wheels or supports lie in the same plane therewith. 20 The ends bear the representation of a door and barred windows all as may be clearly seen by reference to the drawing.

Having thus fully described my new design and pointed out its essential feature, as well 25 as the details of the same, as illustrated in the drawing, I claim—

The design for a paper box substantially as herein shown and described.

HERMAN GOETTSCH.
